7 Claims. (Cl. 29—157.4)

This invention relates to improved means and method of constructing tubular walls and particularly walls of tall furnaces which are faced with fluid cooled tubes.

The furnace walls of large steam generators are commonly lined with steam generating tubes which are connected into the water circuits of the generator. The furnace height which in large boilers may exceed one hundred feet is in most cases made up of several tube lengths. This requires the field welding of a multiplicity of tubes end to end to form continuous conduits extending from the bottom to the top of the furnace wall. A great number of such conduits arranged in parallel rows cover the furnace walls and are connected to bottom and top headers or drums for parallel flow of fluid therethrough.

Heretofore such a tubular wall was completely erected in the field, each tube length of a circuit being separately raised and held in place while adjoining tube length ends were aligned and welded together. The tubes were cut to length in the shop and when tubes were cut to improper length, as frequently occurred, correction of the error in the field involved additional cutting, grinding and scarfing. When using the above mentioned conventional method of constructing tall tubular walls composed of relatively small diameter tubes arranged in substantial side by side contact, the cost involved for erecting such walls became so high as to be uneconomical.

It is accordingly a primary object of the invention to provide a novel and improved method of constructing a tubular wall of the type mentioned above, including the bending and welding in unison of tubes forming group components of such a wall, whereby the cost of constructing these walls is substantially reduced.

It is a further object of the invention to provide a novel and superior apparatus and method for supporting and aligning adjacent tube ends while welding them together thereby facilitating and increasing the quality of workmanship to a considerable extent.

Another object of the invention is to provide a superior method of bending the wall tubes in unison, thereby contributing considerably to a reduction of the overall cost of fabricating and erecting tall tubular wall furnaces so as to make their use economically attractive.

Additional objects and advantages will become apparent from the following description of illustrative embodiments of the invention when read in conjunction with the accompanying drawings wherein:

Fig. 1 is a sectional elevation of a typical steam generator furnace having fluid cooled tubular furnace walls.

Fig. 2 is an enlarged front elevation of a typical section of the tubular furnace walls of Fig. 1.

2

Fig. 3 is a side elevation of the wall section of Fig. 2 and taken on line 3—3 of Fig. 2.

Fig. 4 is an isometric view of a group of tubes assembled to form a typical tube panel and showing means for tying and protecting the tube panel during subsequent operations of bending, shipping, erecting and welding.

Fig. 5 is a perspective view illustrating how the tubes are shaped to a desired contour in a bending press while united in a tube panel.

10 Fig. 6 is a side elevation of two tube groups or panels arranged end to end and with their ends sprung apart prior to welding by means of our improved apparatus.

Fig. 7 is a cross section taken on line 7—7 of Fig. 6 showing the tubes separated in the position ready for welding.

15 Fig. 8 is a cross section similar to Fig. 7 but showing the position of the tubes and that of the improved apparatus before the tubes are sprung apart for welding or after they have returned to their natural position after welding.

20 In Fig. 1 there is diagrammatically illustrated a water cooled furnace 10 of a large steam generating unit. Such a furnace is generally of rectangular cross section and as pointed out above may reach an overall height of more than 100 feet. The furnace 10 comprises four walls, two side walls 12a, a front wall 12b and a rear wall 12c. These walls are lined with tubes 14a, 14b and 14c respectively. The ends of tubes 14a are connected to lower headers 16 and upper header 18. The ends of tubes 14b and 14c are connected to lower drums 20 and upper header 22. Upper headers 18 and 22 in turn communicate with steam and water drum 24 by way of tubes 26 and 27 respectively, and lower headers 16 are connected to drums 20 by tubes 28. There is provided a steam and water drum 24 which communicates with drums 20 by way of pipes 30 thereby establishing a number of water circulation circuits throughout the furnace walls 12a, 12b and 12c.

25 Fuel and air which is introduced into furnace 10 by burners 32, burns within the furnace, liberating heat and generating steam in tubes 14a, 14b and 14c. The steam rises and is collected in drum 24 from where it is withdrawn at 33 for further heating and use. The steam is replaced by feed water entering drum 24 at 34.

30 According to the invention the tubular water cooled lining of each wall of furnace 10 is subdivided into numerous wall sections or tube panels. For example side wall 12a is subdivided into three tiers of panels 36a, 36b and 36c.

35 In Fig. 2 these panels are shown in enlarged scale and are typical of the construction proposed by our invention and applicable to all four walls of furnace 10.

40 Thus this typical wall here designated 12 comprises top and bottom headers 18 and 16 respectively interconnected by a bank of parallel tubes 14 having substantial side by side contact, lying in a common plane, and facing the interior of the wall structure 12. The wall structure 12 may include any well known refractory-insulation-casing construction on the exterior of tubes 14 (not shown). Because of the distance between headers 16 and 18 which exceeds that of a tube length suitable for shipping, two or more tube lengths 14 are welded end to end at 38 to form a continuous conduit between headers 16 and 18, and this welding is done in the field. As mentioned above, such a tubular wall was heretofore completely erected in the field, each tube of each circuit be-

tween headers being separately raised and held in place while adjoining tube ends were aligned and welded together. This method is very slow and costly.

According to our invention similar groups of tubes 14 such as the groups 36a, 36b and 36c shown in Figs. 2 and 3 are separately assembled in the shop. Each group contains a multiplicity of tube lengths 14 in parallel as illustrated in Fig. 4. All lie in a common plane having a width and length suitable for handling in transport and erection in the field. For example the width of such a group may be about four feet and the length about forty feet. All tube lengths 14 of a group are usually of the same length and their end surfaces 40 and 42 are in alignment generally at right angles to their axes. Such end alignment of the tubes 14 in a group is provided in the shop by fastening them together adjacent their mid lengths, as by welding as shown at 44 (Fig. 1). Stiffening members or strongbacks 46 (see Fig. 4) are additionally provided on opposite sides of the tubes of a group, together with means to support the strongbacks snugly against the tubes, such as by banding irons 48 (Fig. 4). The ends of tubes 14 of a group are protected against injury, or disalignment with the ends of the remaining tubes, by means such as the channels 50 (Fig. 4) which extend over the tube ends for the full width of the tube panel.

Turning now to Fig. 3 the ends 42a and 40a of alternate tubes 14 of groups 36a, 36c adjacent the headers 18 and 16, respectively, are offset with respect to the remaining tube ends. Preferably the headers contain welded in nipples 52 which register alignment with the ends of the tubes 14 and are welded thereto in the field. This is indicated at 38a in Figs. 2 and 3.

The above described method and means for assembling tubes into groups of tubes or tube panels 36a, 36b, 36c and as shown in Fig. 4 is typical for all groups and the alignment of each group is so maintained during subsequent bending operations, during transport from the shop to the field and during welding in the field.

As can be noted from Fig. 1 the furnace walls 12b and 12c contain tube groups which have two or more bent portions such as at 54. These tubes heretofore had been bent separately in the shop. Our improved method of constructing tubular water wall furnaces of large dimensions includes multiple or gang bending, i.e., the bending of these tubes in unison while assembled in tube panels such as that shown in Fig. 4.

The method of bending a tube panel to conform to the contour of a particular furnace wall such as for example 12b or 12c, of which it is to become a part, is pictorially shown in Fig. 5.

Panel 36 is hoisted and supported by hoist 58 while the portion of the panel which is to be bent is operatively engaged with the bending rollers 60 of bending press 62. While this operation is performed the entire tube panel comprising perhaps 35 individual tubes is handled and bent as in one piece, instead of handling and bending 35 separate tube lengths, which had been the practice heretofore.

After the multiple bending operation the panel is ready for shipment to the erection site along with other panels which do not require bending.

In the field, neighboring groups of tubes or panels are prepared for the hoisting of these panels to the desired position in the respective furnace wall. These preparations include the attaching in the proper location on the tube panel of our herein disclosed raising-supporting-aligning jig, the function and design of which will now be considered in detail.

As pointed out earlier in this discussion, tube panels, such as 36a, 36b and 36c for example, in their final position as component parts of a furnace wall, are arranged with their ends 40 and 42 adjoining and their axis in alignment thereby bringing all the tubes of both groups

into a common plane for forming continuous conduits from the bottom header 16 to the top header 18.

Because the tubes are in substantial longitudinal contact, the adjoining ends (see Fig. 6) of alternate aligned tubes of the groups 36a and 36b respectively must be offset from the remaining tubes, or sprung apart to provide access to the ends for welding them together. Preferably the alternate tube ends 40b, 42b are offset to one side of the common plane of the wall and the remaining tube ends 40, 42 are offset to the other side of said plane.

In Figs. 6, 7 and 8, one form of means is disclosed to accomplish the offsetting of the tube ends according to this invention before they are hoisted to the assigned position in the furnace wall. There are shown two jigs 64 and 66, jig 64 being mounted on tube group 36a and jig 66 being mounted on tube group 36b adjacent the tube ends. Each jig comprises two channel beams 68 placed on opposite sides of the tubes 14 and opposite each other. Referring now to Fig. 8 each channel beam 68 has lugs 70 fastened thereto which preferably are spaced longitudinally of the channel on centers equal to about twice the spacing of the centers of tubes 14 and which extend outwardly from the channel toward the tubes for a distance about equal to the diameter of the tubes and terminate in flat faces 72 which bear against the tube surface. The lugs 70 on one channel beam 68 are staggered with respect to the lugs 70 on the opposite channel and when the channels are moved toward each other, the lugs force alternate tubes against the opposite channel, thereby deflecting the tubes so that the center lines of the end portions of the tubes lie in planes parallel to the common plane of the tube wall, as shown in Figs. 6 and 7.

The two jigs 64 and 66 being of the same size and acting in the same manner will offset the ends of the tubes of groups 36a and 36b by the same amount. Holding lugs 74 (see Fig. 6) are welded onto selected tubes 14 to provide stops for jigs 64 and 66. Each jig is provided with bolts 80 and 82 for forcing the channel beams 68 together. Each bolt forms an angle of about 45° with the longitudinal axis of the channels and is provided with nuts at each end which bear against angles 83 secured to the inside of channel 68 by welding. However the angle of bolt 80 is opposite to that of bolt 82 so that when the bolts are uniformly pulled up any relative longitudinal movement of the channels may be avoided. The angular position of the bolts permits the bolts to pass between the tubes when these are offset. Although only one pair of bolts 80 and 82 are shown in Figs. 7 and 8 several pairs of these bolts are employed on panels of greater width and accommodating a larger number of tubes.

Additional members 75 are attached such as by welding to the channels 68 on one side of jigs 64 and 66 by which the entire assembly of the jigs and the tube group is lifted to their appointed place on the wall with tube ends 40 and 42 adjoining. Channel beams 68 are also provided with pipe sections 76 through which bolts 78 are passed from jig 64 to jig 66 to align and space them after the tube panels 36a and 36b have been raised to their respective positions as components of the furnace wall. Having thus aligned the corresponding tube ends 40 and 42, 40b and 42b the tubes are then welded together at 38, two men working on each tube on opposite sides.

After the welding of all tubes is completed jigs 64 and 66 are removed and tubes 14 allowed to spring back and to assume their original position in the plane of the wall. Lugs 74 of course are also removed as well as strong backs 46. Under certain conditions it may be found desirable to remove the strong backs before the tube panels are raised in welding position and rely entirely on weld 44 to keep the central portion of the tubes of the panel aligned and united.

Our invention accordingly as hereinabove set forth, provides for a simple and advantageous method of constructing the walls of tall furnace chambers lined with closely spaced parallel tubes. The invention thus permits the realization of outstanding savings in man hours both in the production stage through the use of multiple or gang bending of tubes and in the erection stage through the additional use of our novel raising-supporting-aligning jigs.

While we have here shown a novel and superior method of constructing tubular walls and described an illustrative embodiment for practicing our method it will be understood that changes in construction, combination and arrangement of parts as well as certain changes in the sequence of the method steps may be made without departing from the spirit and scope of the invention as claimed.

We claim:

1. A method of constructing a fluid cooled tubular wall by aligning upright tube panels end to end, each panel being composed of a row of parallel upright tubes, comprising the steps of forming at least two tube panels each by aligning a plurality of tube lengths in side by side parallel relationship; securing each tube of each panel to an adjacent tube thereof at a point of said tube remote from the free ends thereof; springing said free ends of alternate tubes of said one panel and corresponding free ends of alternate tubes of said other panel out of position in a direction lateral to said panel while keeping respective tube ends in alignment; raising said panels into the desired wall position so that the tube ends of one panel abut and are aligned with the tube ends of an adjacent panel; welding the tube ends of one panel to the corresponding tube ends of the adjacent panel while thus aligned; and releasing said tube ends to allow said alternate tubes to spring back and resume their original positions.

2. A method of constructing a fluid cooled tubular wall by aligning tube panels tube end to tube end, each panel being composed of a row of parallel tubes, comprising the steps of forming at least two tube panels, each by aligning a plurality of tube lengths in side by side parallel relationship; securing each tube of each panel to an adjacent tube thereof including at a point of said tube remote from the ends thereof; subjecting at least one selected panel to exterior forces whereby to cause the simultaneous bending of the tubes of said panels to a predetermined contour characteristic of said wall; freeing and subsequently springing the ends of adjacent tubes of said one panel and corresponding ends of adjacent tubes of said other panel out of position an equal distance in a direction lateral to said panel while keeping respective tube ends in alignment; raising said panels into the desired wall position so that the tube ends of one panel abut and are aligned with the tube ends of an adjacent panel; welding the tube ends of one panel to the corresponding abutting tube ends of the adjacent panel while thus aligned; and releasing said tube ends to allow said alternate tubes to resume their original positions.

3. A method of constructing a fluid cooled tubular wall by aligning tube panels end to end, each panel being composed of a row of parallel tubes, comprising the steps of forming at least two tube panels, each by aligning a plurality of tube lengths in side by side parallel relationship; securing each tube of each panel in alignment with an adjacent tube thereof including at a point of said tube remote from the ends thereof; subjecting at least one selected panel to exterior forces whereby to cause the simultaneous bending of the tubes of said panel to a predetermined contour characteristic of said wall; raising said panels into the desired wall position so that the tube ends of one panel abut and are aligned with the tube ends of an adjacent panel; freeing and subsequently springing the ends of adjacent tubes of the one panel and the ends

of the corresponding tubes of the other panel out of position in the same lateral directions the same distance, keeping respective tube ends in alignment; welding the tube ends of one panel to the abutting tube ends of the adjacent panel while thus aligned; and releasing said tube ends to allow the tubes to resume their original positions.

4. A method of constructing a fluid cooled tubular wall of uneven contour by aligning elongated tube panels end to end, said panel being composed of a row of parallel tubes which are bent to conform to said contour of said wall, comprising the steps of forming at least two tube panels that are component parts of said wall by aligning a plurality of tube lengths in side by side parallel relationship; securing each tube of each panel in alignment with an adjacent tube at a point remote from the ends of said tubes, with said ends remaining free; subjecting at least one selected panel to exterior forces whereby to cause the simultaneous bending of the tubes of said panel to said predetermined contour characteristic of said wall, raising said panels into the desired wall position so that the said free tube ends of one panel abut and are aligned with the tube ends of an adjacent panel; spreading apart the same distance selected ones of said free tube ends to form end to end aligned pairs between abutting panels; and welding said tube ends of one panel to the corresponding tube ends of the adjacent panel while thus spread apart and aligned.

5. In a method of constructing a tubular wall by stacking tube panels tube end to tube end, each panel being composed of a multiplicity of side by side aligned tubes lying in a common plane the tubes of one panel and the tubes of the abutting panel being connected end to end, the steps which comprise shop assembling similar groups of said tubes, each group comprising single length tubes aligned side by side in a plane and fastened together at least at two points along their lengths, maintaining said alignment during transport to the field, assembling said groups to form said tubular wall with said tubes in said common plane in end to end alignment, releasing and freeing a sufficient portion of each tube and to permit the spreading apart of said ends, offsetting by springing apart the same distance the ends of adjacent tubes out of said common plane into a plane parallel thereto, joining said aligned ends of said tubes by welding while being so offset and thereafter releasing said tubes to spring out of said deflected offset back into alignment into said common plane.

6. In a method of constructing a tubular wall composed of vertically aligned tube panels formed of a multiplicity of side by side aligned tubes lying in a common plane, said panels being connected end to end, the steps which comprise shop assembling similar groups of said tubes, each group comprising single length tubes lying closely side by side in a plane and fastened together adjacent their mid lengths with their ends in alignment, maintaining said alignment during transport to the field, freeing said ends and offsetting by springing apart said free ends of alternate tubes to one side of and the ends of the remaining aligned tubes to the other side of said common plane into planes parallel thereto, assembling said groups to form said tubular wall with said tubes in said common plane in end to end alignment, joining said adjacent ends by welding while so offset and thereafter releasing said tubes to spring out of said deflected offset back into alignment into said common plane.

7. In a method of constructing a tubular wall comprising aligned tube panels formed of a multiplicity of relatively small diameter tubes lying in a common plane side by side, said panels being connected end to end, the steps which comprise shop assembling similar groups of said tubes, each group comprising single length tubes lying side by side in a plane with the tubes in substantial contact and welded together adjacent their mid lengths with their end surfaces in alignment at right angles to their axes, maintaining said alignment during transport to the

field, freeing said ends and offsetting, by springing apart the adjacent free ends of alternate aligned tubes to one side of and the said free ends of the remaining aligned tubes to the other side of said common plane into planes parallel thereto and with the tube centers at least about one tube diameter apart, assembling said groups to form said tubular wall with said tubes in said common plane in end-to-end alignment, joining said adjacent ends by welding while so offset and thereafter releasing said tubes 10 to spring out of said deflected offset back into alignment into said common plane.
